David Clark, a citizen of,

Letters Patent.

The document referred to in these Letters Patent and making part of the same, containing a description in the words of the said David Clark himself of his marble and pipe stone turner.

There is a vertical bog wheel on a horizontal shaft of this machine which is turned by water or other force and conveys motion to a tumbler head standing upright this tumbler head turns by a flat or small spur wheel or vertical auger for boring stone for pipes for aqueducts or other purposes and it also turns the bit, or instrument for boring out the hollows in stone blocks of every description by means of a spur wheel and pinion on the perpendicular shaft of the bit. The stone to be bored by this last mentioned bit is placed in a bason trough of water under the bit. On one side of the machine is an horizontal lathe, turned by a shaft which passes round the first vertical wheel and round a wheel or, pully on the Mandrel of the lathe the rest of the chisel or turning tool is secured to the tool and projects beneath it. In all cases where a trough of water can be used for the stone to lie in whilst turned or cut it must be so placed; and in other cases kept constantly wet during the operation. This machine is for manufacturing bowls, plates, mortars and mugs or flat or hollow ware of every description out of stone or marble as also for boring and turning aqueduct pipes, flues etc. &c. The number and kind of bits or tools are varied according to circum-
stances.
